RADIATING HORN

Jacob R. Bisser, Belmont, and Raymond J. Włodkowiski, Attleboro, Mass., assignors, by mesne assignments, to the United States of America as represented by the Secretary of War

Application January 3, 1946, Serial No. 638,888

4 Claims. (Cl. 250—33.63)

1

This invention relates to horn type radiating elements for high frequency communication systems or to tapering sections of wave guide transmission lines and more particularly to a horn of which the flare angles may be variable.

In order to determine the impedance and radiation characteristics of horns or transition portions between uniform and tapered wave guide transmission lines, it has heretofore been necessary to construct many different horns or transition sections having various angles of flare which has resulted in considerable loss of time, expense and materials.

It is one of the objects of the present invention to prevent or minimize such loss by providing a novel type of horn or transition section in which the flare angle in at least one plane is variable.

It is another object of the invention to provide a variable angle horn or transition section for use as a precision test apparatus from which the radiation pattern and impedance characteristics may be determined.

For a better understanding of the invention together with other and further objects thereof, reference is had to the following description, taken in connection with the accompanying drawing, in which:

Fig. 1 is a plan view of a variable angle horn radiating element or a wave guide transition section according to the present invention;

Fig. 2 is a front elevation view of the device of Fig. 1; and

Fig. 3 is a sectional view of the same along the line 3—3 of Fig. 1.

In the drawing, the horn or transition section 10 comprises a wave guide portion 11 of substantially rectangular cross section having top and bottom walls 12 and 13 and side walls 14 and 15, connecting at throat portion 16 with the flared portion 17. Flared portion 17 comprises substantially fan-shaped top and bottom plates 18 and 19 connected to or extending from the top and bottom walls 12 and 13, respectively, of wave guide portion 11, and lying in substantially the same planes therewith, and movable side plates 20 and 21 flaring away from each other and preferably disposed at substantially equal angles to the planes of the side walls 14 and 15, respectively of wave guide portion 11. The fan-shaped top and bottom plates 18 and 19 may be separated in the flared portion by two spacing members 22 and 23 and in the throat portion 16 by the supporting side walls 14 and 15 of wave guide portion 11. In order to keep the wave-

2

length, of the rectangular guide portion 11, constant in the transverse electrical field throughout the flared portion between movable side plates 20 and 21, it is important to maintain the top and bottom walls 12, 13 of wave guide 11 and the top and bottom plates 18 and 19 parallel within a tolerance of plus or minus .003". The spacing between the supporting walls 14 and 15 is preferably made equal to the dimension of a wave guide to which the horn is to be attached or for which flaring is desired and the characteristics thereof tested.

The supporting side walls 14 and 15 at the throat end thereof are cut back away from the wave guide aperture as at 24 and 25 in the form of a taper so that the edge of each wall is brought to a knife edge 25'. The movable side plates 20 and 21 are also cut back as indicated at 26 and 27 and tapered to a knife edge 27' at the throat end thereof. The respective knife edges 25' and 27' of side walls 14 and 15 and movable plates 20 and 21, respectively, are positioned very close together so that the respective knife edges are in close parallel alignment. Preferably, the knife edges are spaced by not more than about 0.003".

Exactly in line with the inside edges of side walls 14 and 15 and about 0.003" from their knife edge points are the centers of two circular bores or sockets 28 and 29, in the top and bottom plates 18 and 19, respectively. Rotatably fitted in the two aligned bores 28 and 29 are substantially cylindrical pivot or knob members 30 and 31 which fit flush with the inside surfaces 35 of the top and bottom plates 18 and 19. The movable plates 20 and 21 have their top and bottom edge surfaces adjacent the knife edge portion, welded, soldered or otherwise secured as at 30' and 31' to the inside surface of the top 40 and bottom pivot members 30 and 31 with the inside surfaces of movable plates 20 and 21 in strict alignment with the pivot centers, and with the knife edges 27' being perpendicular to the inside surfaces of the pivots 30 and 31 at 45 the centers, thereof. By this arrangement, the movable plates 20 and 21 are adapted to pivot about the axis through the centers of pivots 30 and 31 while maintaining their close proximity to the knife edges 25' of side walls 14 and 15. Thus by means of this precision knife edge joint, the movable plates 20 and 21 may be rotated to any angle relative to side walls 14 and 15 without changing the location of the corners. It is important that the position of the corners be kept 50 precise because the impedance of the tapered

guide is a function of the distance from each knife edge 27' to the apex of the angle formed by the extensions of the movable plates 20 and 21; the radius must be, therefore, a known factor. The top and bottom edges of the movable plates 20 and 21 are preferably machined perfectly flat in order to insure both freedom of motion between the parallel plates 18 and 19 and constancy of the guide wavelength throughout the horn or transition portion 10.

To facilitate securing the movable plates 20 and 21 in correct position, an arm member 32 having an arcuate slot 33 therein is attached intermediate the length of the outside surface of each movable plate 20 and 21 as at 33'. The movable plates 20 and 21 may be pivoted to any desired position by moving the arms 32, each of which may then be secured in place by means of a lock-nut 34 engaging threaded bolt 35 which is secured to an extension 36 of lower plate 19 and projects upwardly through slot 33.

Secured to the upper portion of each pivot knob 30 as by screws 37 is a pointer member 38 preferably having a straight edge disposed radially of the pivot knob 30, the pointers 38 being secured in position with their straight edges in strict alignment with the inside edges of the movable plates 20 and 21. If desired, a calibrated scale, in degrees, may be marked on the top surface of plate 18 whereby movement of movable plates 20 and 21 to a certain angular position may be determined by the pointer member 38. Thus, the position of the pointer member 38 on the protractor scale indicates the angle of each movable member and thereby the angle of flare of the horn relative to side walls 14 and 15 of wave guide portion 11.

In order to find a radiation pattern or impedance characteristics of a horn of a particular geometry, the test horn 10 according to the invention is set so that the movable plates 20, 21 are positioned to the angle required. The free end of the wave guide portion 11 is attached to the wave guide in the system and tests made in a well-known manner. If necessary, the flare angle of the test horn 10 may be changed to vary the characteristics. By this arrangement, it is possible to determine the proper geometry of a horn for any desired system before actually constructing the same. In order to measure the impedance characteristics of the corner formed between a uniform wave guide and a tapered wave guide, the test horn 10 as described may be used as a transition section and shorted to produce the known impedance at the corner, i. e., impedances equal to zero, infinity and $\sqrt{-1}X$.

While there has been described what is at present considered the preferred embodiment of the invention, it will be obvious to those skilled in the art that various changes and modifications may be made therein without departing from the invention.

What is claimed is:

1. A horn adapted to have various angles of flare comprising a rectangular wave guide portion having top, bottom and side walls and a flared portion in communication with said wave guide portion at the throat portion of said horn, said flared portion comprising substantially fan-shaped parallel top and bottom plates extending from and in the same planes with the top and bottom walls respectively of said wave guide portion and movable side plates having their top and bottom edges in substantially slidable engagement

with the inside surfaces of said top and bottom plates, the throat ends of the side walls of said wave guide portion and of the movable side plates of said flared portion being cut back to substantially form knife edges perpendicular to said top and bottom plates at the inside corners of each of said wave guide side walls and said movable side plates, the knife edge of each movable plate being in very close parallel relation to the knife edge of the adjacent wave guide side wall, circular bores in both the top and bottom plates having their axes coinciding with the knife edges of said movable plates, pivot members rotatably seated in said bores having their inner surfaces flush with the inner surfaces of said top and bottom plates, the top and bottom edge surfaces of said movable plates adjacent said knife edges thereof being secured to the adjacent inner surfaces of said pivot members whereby each movable plate is rotatable about its knife edge as an axis and whereby the inner surface of each movable plate is adapted to be positioned at any desired angle relative to the inner surface of the adjacent side wall of said wave guide portion.

2. A horn as claimed in claim 1 wherein a pointer member is secured to the outer portions of each of the pivot members in the top plate, each pointer member having a straight edge lying in the plane of the inner surface of the corresponding movable plate and wherein a protractor scale is marked on the upper surface of said top plate whereby the position of said pointer members relative to said scale determines the exact angular position of said movable plates relative to the inner surfaces of the side walls of the wave guide portion.

3. A horn as claimed in claim 1 wherein said horn is adapted to form a transition section between a uniform wave guide and a tapered wave guide.

4. A precision test apparatus for predetermining the radiation patterns and impedance characteristics of radiating horn elements and of transition sections between uniform and tapered wave guide, comprising a horn, including a wave guide portion including side walls and a flared portion of the horn having side plates which are movable, the adjacent ends of said movable plates and of said side walls being brought substantially to knife edges at the inside corners thereof, said adjacent knife edges being in very close parallel relation, and means for rotatably mounting said movable plates so that each of said movable plates is adapted to rotate about its knife edge as an axis.
